CLAIM

The ornamental design for a hand glove with dual zippers,
as shown and described.

DESCRIPTION

FIG. 1 shows a top and side perspective view of a hand glove
with dual zippers.

FIG. 2 shows a bottom plan view thereof.

FIG. 3 shows a top plan view thereof.

FIG. 4 shows a first side elevation view thereof.

FIG. 5 shows a second side elevation view thereof.

FIG. 6 shows a third elevation view thereof.

FIG. 7 shows a fourth elevation view thereof; and,

FIG. 8 shows two hand gloves with dual zippers.

The evenly dashed broken lines outside the claim boundary
depict portions of a hand glove with dual zippers and form
no part of the claim. The dash-dot-dot dash broken lines
depict the claim boundary and form no part of the claim. The
evenly dashed broken lines on claimed surfaces depict
claimed stitching.

1 Claim, 8 Drawing Sheets
